UNITED STATES PATENT OFFICE.

WILLIAM A. CAMPBELL, OF PITTSBURGH, PENNSYLVANIA.

COMBINATION-TOOL.

1,277,290.

Specification of Letters Patent. Patented Aug. 27, 1918.

Application filed August 24, 1916. Serial No. 116,651.

To all whom it may concern:

Be it known that I, WILLIAM A. CAMPBELL, a citizen of the United States, and resident of North Side, Pittsburgh, in the county of Allegheny and State of Pennsylvania, have invented a new and useful Improvement in Combination-Tools, of which the following is a full, clear, and exact description, reference being had to the accompanying drawings, forming part of this specification, in which—

Figure 1 is a perspective view of one form of tool, showing the tool blade in the position when one end thereof is adapted for use.

Fig. 2 is a sectional view on the line II—II of Fig. 1, showing the tool in the reverse position.

Fig. 3 is a view similar to Fig 2, showing a modified form.

Fig. 4 is a detail sectional view on a larger scale on the line IV—IV of Fig. 2.

Fig. 5 is a detail face view of one end of one of the handle members, and

Fig. 6 is a detail sectional view on the line VI—VI of Fig. 5.

This invention relates to an improvement in combination tools, and is designed to provide a cheap and efficient device of this character which can readily be made, and which can be sold at a very small cost.

One of the objects of my invention is to provide a self contained tool which comprises a handle formed in such a manner that the handle can be used as a hammer or tack puller, together with a combination tool pivoted to the handle, which may have at one end a putty knife and at the other end a screw-driver; the tool being provided with one or more slots for securing the tool against rotation in either one or both of its positions. The tool is pivoted to the handle by means of an elongated pivotal member, about which the tool is adapted to rotate when it is desired to shift the tool from one position to another position, and which pivotal member is so arranged that it will enter either one of the slots to maintain the tool in rigid position with relation to the handle.

Another object of my invention is to reduce the cost of the pivotal members by striking up projections on one or both of the handle members on opposite sides of the rivet opening, so that a round rivet can be

used for securing the blade in position between the handle members.

The precise nature of my invention will be best understood by reference to the accompanying drawings, which will now be described, it being premised, however, that changes may be made in the details of construction, without departing from the spirit and scope of my invention as defined in the appended claims.

In the drawings, the reference character 2, 2 designate the handle members, and which handle is made from a sheet metal blank bent upon itself, as indicated at 3. The front ends of the members 2 are bent 70 toward each other, and pivotally connected to the handle between the front ends thereof is a blade member having a screw-driver 4 at one end thereof, while the other end thereof is in the form of a putty knife 5. 75 The handle members are provided with recesses 6, 6, while the blade is provided with a similar recess 7, the two sets of recesses being arranged to form a cutter for cutting wire or similar articles. The heel portion of 80 the handle is provided with a tack pulling recess 8 at one edge thereof, while the other edge is provided with a reinforcing member 9 which is adapted to be used as a hammer.

The tool member is provided with a circular opening 10, and extending therefrom is a V-shaped slot member 11 which extends into the blade portion 5, as shown in Figs. 2 and 3, and in which the pivotal member on 90 the handle is adapted to be seated when the blade 5 is to be used, and which is arranged to retain the blade in the position shown in Fig. 2.

In Fig. 3 I have shown a similar blade, 95 and in which the blade member 4 is provided with a similar slot 12 for retaining the blade in position when the end 4 thereof is adapted to be used.

Heretofore in all structures of this character known to me, the rivets for securing the ends of the handle to each other and retaining the blade in position were of elongated form, which greatly increased the cost thereof, as it was necessary to machine these 105 rivets to properly shape them, or to form them in shaping dies.

In the construction shown in the drawings, the retaining member is formed by pressing out portions of the metal of one or 110

both blade members, as indicated at 13 and 14, on opposite sides of a rivet opening 15. If the metal is pressed out on both of the members, the amount of displacement of 5 the metal will be equal to approximately one-half the thickness of the blade, so that the members on the tool members will form stops to prevent the drawing up of the rivet 17 to a point where it would bind the blade member. If, however, these stop projections are only formed on one of the handle members, the amount of displacement of the 10 projections 13 and 14 would be equal to the thickness of the blade.

15 The advantages of my invention result from the provision of a cheap tool which is provided with a tack pulling recess and a hammer at one end of the handle, and which is so arranged that no projections extend 20 any appreciable distance beyond the outline of the handle, so that the device is adaptable to be placed in a pocket. Also from the provision of a compound tool pivotally connected to the forked end of the handle, and which is arranged to be rotated 25 and securely locked in one or both positions without the use of springs or auxiliary devices to maintain the blade in fixed position with relation to the handle. Furthermore, 30 from the provision of means for forming the pivotal member by stamping projections of general V-shape in one of the members which are arranged to seat in V-shaped recesses in the other member, for retaining the 35 blade in a fixed position with relation to the handle.

It will be readily understood by those familiar with the art that, if desired, the 40 projections might be formed on the blade member and a key-slot formed in one of the handle members.

This application forms a continuation in part of my application Serial No. 83,058, filed March 9, 1916.

45 I claim:

1. A device of the character described, comprising a forked handle having pivotal projection formed thereon, a blade member pivotally connected between said members and having an opening to receive said piv-

tal projection, and a rivet for securing said handle members to each other extending through said projection, substantially as described.

2. A device of the character described, 55 comprising a forked handle formed from a sheet metal blank, said blank being folded upon itself and having an inwardly struck pivotal connection on each of said members, a blade member pivoted thereto, and a rivet 60 extending through the handle members and the blade member for securing the blade member in position, substantially as described.

3. A device of the character described, 65 comprising a forked handle formed from a sheet metal blank, there being a V-shaped projection struck up on one end of said blank, a tool mounted between the handle members and having an opening within 70 which said projection is seated, said opening being of cylindrical form in one portion thereof and having a V-slot in another portion thereof for the reception of the projection to retain the blade against movement, and a rivet passing through the handle members and the blade for securing them to each other; substantially as described.

4. A device of the character described, 80 comprising a forked handle formed from a sheet metal blank, said blank having a V-shaped projection struck up on each of its forked ends, there being a rivet opening through each of said projections, a tool having a pivotal opening engaging said projections, the height of said projections being approximately equal to the thickness of the blade, the pivotal opening on the blade having a V-shaped recess for the reception of the projection to retain the blade in fixed 90 position, and a rivet passing through the handle members and the blade for securing the members to each other; substantially as described.

In testimony whereof, I have hereunto 95 set my hand.

WILLIAM A. CAMPBELL.
